DESIGN FOR A ROLLING PEN-CIL

James Jernigan Sanders, Nashville, Tenn.

Application April 30, 1945, Serial No. 119,326

Term of patent 7 years

(Cl. D74—24)

To all whom it may concern:

Be it known that I, James Jernigan Sanders, a citizen of the United States, residing at Nashville, in the county of Davidson and State of Tennessee, have invented a new, original, and ornamental Design for a Rolling Pen-Cil, of which the following is a specification, reference being had to the accompanying drawing, forming part thereof.

The figures are described as follows:

Fig. 1 is a horizontal elevational view of the rolling pen-cil showing my new design.

Fig. 2 is an end view thereof; and,

Fig. 3 is an exploded view of the same.

The essential features of my design reside in the parts shown in full lines.

I claim:

The ornamental design for a rolling pen-cil, as shown and described.

JAMES JERNIGAN SANDERS.
